APPARATUS FOR DRESSING CONVEX SURFACES ON GRINDING WHEELS

Joseph Klopak, Newark, N. J., assignor to General Motors Corporation, Detroit, Mich., a corporation of Delaware

Application April 8, 1949, Serial No. 86,254

5 Claims. (Cl. 125—11)

1

This invention relates to apparatus for dressing convex surfaces on grinding wheels, especially large radius curves on wheels of large diameter. In prior apparatus for dressing convex curves, the apparatus has been subject to vibration and, in order to get the center of curvature inside of the body of the wheel, a large pivoted yoke has straddled a large portion of the wheel. This leads to undesirable bulk and expense.

An object of the invention, accordingly, is to provide a dressing apparatus which will avoid the above mentioned and other defects in prior devices. Another object is to provide a compact but rugged dressing apparatus which will dress any selected convex curve across the periphery of a grinding wheel and be free from vibration. Another object is to provide improved apparatus for locating the center of curvature about which the dressing tool travels inside the body of the wheel with provision for varying the radius of the curve produced without the need of a plurality of templates or formers.

In the drawings,

Fig. 1 is a plan view with a splash guard in section.

Fig. 2 is a view of parts of Fig. 1 in another position.

Fig. 3 is a perspective view of a blade and its follower.

Fig. 4 is a front view of Fig. 1.

Fig. 5 is a side view of Fig. 1 with a slide in section.

Fig. 6 is a plan view of a slide.

Fig. 7 is a perspective view of a gauge.

A main bracket 2 has a base flange 4 secured by screws 6 to the grinding wheel head. The bracket has a platform 8 on which is fastened a dovetail guiding tongue 10 whose center is in line with the central plane of the grinding wheel G. A slide 12 having guide rails is shiftable along the guide by a screw 14 threaded in a nut 16 on the slide and journaled for rotation without endwise movement in a plate 18 fastened to the platform. Fastened in a recess of the slide 12 is a profile blade or template 20 having an arcuate guiding edge 22 engaged by the tip of a wedged shaped follower 24 formed on a stud 26 which secures the follower to a swinging diamond carrying arm 28. The follower has a flange 30 extending under an overhanging portion of the blade to hold the arm 28 down on the top of the plate 12. The follower and its flange are shiftable in an arcuate recess 32 of the slide 12. The enlarged front of the arm 28 has a threaded recess to adjustably receive a threaded diamond holder 34 in which a headed stud carrying a cutting tool or

2

dressing diamond 36 is secured. A curved splash guard 38 having an opening for the arm 28 is guided between curved angle plates fastened on a main splash guard 40 which substantially follows the outline of the slide 12.

The arm 28 is connected to a longer arm 42 by parallel links 44 and 46 of equal length pivoted to each arm. The front end of the longer arm is pivoted to the slide 12 at one side of the wheel 10 by a pivot stud 48 which is connected by a coil spring 50 to a stud on the link 46. The spring holds the follower pressed against the profile blade. Pivoted to the arm 42 is a link 52 which is in turn pivoted in the fork of a yoke 54 adjustably secured to one end of a piston rod 56 projecting from a cylinder 58 secured to the slide 12.

The piston and cylinder unit oscillates the arm 42 about its pivot 48 and the parallel links cause the diamond carrying arm 28 to follow in parallelism. While this occurs the follower 24 is kept pressed against the profile blade thus controlling the motion of the diamond in an arc. The center of the curvature to be produced on the grinding wheel is inside the body of the wheel as indicated

25 at C in Fig. 1; a plane perpendicular to the side of the grinding wheel through this point C will also pass through the center of the pivot stud 48. This condition is maintained whatever the radius of the curvature to be produced. The curvature 30 of the profile blade has the same center of curvature as the curvature to be produced on the wheel but it has a larger radius.

Actuation of the screw 14 adjusts the slide 12 to locate the pivot 48 so that the center C which 35 corresponds to it will come at the desired distance from the periphery of the wheel. If a larger radius of curvature is desired, the slide 12 and its appurtenances are advanced towards the wheel and the diamond holder 34 is adjusted 40 away from the wheel by the same amount by turning it in its threaded recess. The foregoing shifts the center C deeper into the wheel. If a smaller radius of curvature is desired, the slide 12 and its appurtenances are retracted from the 45 wheel and the diamond holder is advanced the same amount. The profile blade serves as the guide for every radius desired. Its arcuate curvature is a known constant and its center of curvature is always at the center of curvature to be produced. The radius of the curvature to be produced is the distance from the diamond to the plane through the pivot 48 perpendicular to the side of the wheel. The apparatus is not limited to the dressing of arcuate curves. Other forms 50 can be dressed by blades of the selected shapes.

Fig. 6 shows a set-up gauge 60 for accurate

location of the diamond holder in the arm 28. The gauge (shown enlarged) will fit around a portion of the diamond holder and when its arcuate edge 62 is placed against the end of the arm 28, the diamond holder can be shifted to make the diamond just meet the bottom wall 64. The amount that the diamond projects from the arm 28 is then the known depth of the gauge. The distance of the end of the arm from the edge of the blade is a known constant.

I claim:

1. In apparatus for forming a convex curve across the periphery of a grinding wheel, a long arm pivoted at one side of the grinding wheel, the pivot lying in a plane intersecting the wheel at right angles, a second and shorter arm normally in the central plane of the grinding wheel, links pivotally connecting the arms in parallelism, a cutting tool at one end of the shorter arm, a follower on the shorter arm, a convex profile blade extending across the plane of the grinding wheel and having its center of curvature within the body of the wheel and in the aforementioned intersecting plane, a spring urging the follower against the blade, and means operatively connected to the longer arm for oscillating the longer arm around its pivot to traverse the follower along the blade.

2. In apparatus for dressing a convex surface of revolution on a grinding wheel, a movable arm normally in the plane of the grinding wheel, a cutting tool at one end of the arm and engageable with the grinding wheel, a profile blade having an arcuate surface crossing the plane of the grinding wheel and having its center of curvature within the body of the grinding wheel, a follower on the arm and engaging said arcuate surface on the profile blade, a spring urging the follower into engagement with said arcuate surface, mechanism including a pivoted member and pivoted parallel links holding the movable arm radially of said arcuate surface and oscillating mechanism connected to said pivoted member.

3. In apparatus for forming a convex curve across the periphery of a grinding wheel, a long arm pivoted at one side of the grinding wheel, a second and shorter arm beside the first, links pivotally connecting the arms, a cutting tool at one end of the shorter arm and engageable with the grinding wheel, a profile blade having a con-

5 vexed surface extending across the plane of the wheel and having its center of curvature within the body of the wheel, oscillating mechanism operatively connected to the longer arm for swinging said longer arm about its pivot, and a follower engaging the convexed blade surface for controlling the motion of the shorter arm.

10 4. In apparatus for forming a convex curve across the periphery of a grinding wheel, a slide, an arm pivoted to the slide at one side of the grinding wheel, a second arm, parallel links pivotally connected to the arms, the slide having an arcuate slot, a profile blade secured to the slide and overhanging the slot, a follower secured 15 to the second arm and entering the slot to ride along the blade, a cutting tool carried by the arm, oscillating mechanism connected to the first mentioned arm, an adjustment member for shifting the slide towards and from the periphery of the wheel to select the position of the center of oscillation, and an adjustable holder locating the cutting tool lengthwise of the second arm.

20 5. In apparatus for forming a convex curve across the periphery of a grinding wheel, a slide, an arm pivoted to the slide at one side of the grinding wheel, a second arm, parallel links pivotally connected to the arms, a profile blade secured to the slide and having an arcuate surface crossing the plane of the grinding wheel, a follower secured to the second arm and urged against the blade, a cutting tool adjustably secured to the second arm, mechanism operatively connected to one of said arms for oscillating the 25 first mentioned arm to cause the follower to traverse said arcuate surface, and feeding mechanism connected to the slide for shifting the slide towards or from the wheel to select the position of the center of oscillation.

30 40 35 JOSEPH KLOPAK.
